LUDWIG DÜRR, OF FRIEDRICHSHAFEN, GERMANY, ASSIGNOR TO LUFTSCHIFFBAU-
ZEPPELIN GESELLSCHAFT MIT BESCHRANKTER HAFTUNG, OF FRIEDRICHSHAFEN,
GERMANY.

GAS-CELL PROTECTION FOR AIRSHIPS.

Application filed September 13, 1924, Serial No. 737,593, and in Germany September 25, 1923.

My invention relates to means for protection of gas cells of airships against penetration by any solid bodies that might be thrown against them, such for example as 5 pieces of ice which may get into one of the propellers and thereby be thrown against the adjacent gas cell.

Airships when travelling through the air at a low temperature and in moist weather 10 may become covered with ice at certain spots, especially on metallic parts, such as for example the gearing cases of the propellers or the struts holding these cases. The vibration of such parts resulting from the 15 motors may cause such pieces of such ice to fall off and when by chance they fall into the turning propeller they may be thrown sideways and be driven against the ship's body. Since they have received a 20 great momentum from the propeller they may pierce right through the ship's envelope and penetrate through the wall of the gas cell situated behind the outer cover. This will cause a leak in the cell which 25 may become dangerous to the ship by allowing part of the lifting gas to escape.

Here my invention will be of great advantage. By special means I counteract the energy of the solid body approaching 30 the wall of the cell and diminish it to such a degree that the solid body will not have force enough to pierce the wall of the gas cell. Such means are for example one or 35 more layers of a fabric of considerable tensional strength arranged outside of the gas cell in a loose and resilient way. For reinforcing such arrangement a strong net or the like may be added. Of course the protective layer must be at a certain distance 40 from the wall of the gas cell. In this distance the energy of the piece of ice or whatever it be that is caught in the protective layer must be either absorbed entirely or at least to such an extent that the energy is 45 reduced to such a point that there is no danger of penetrating the wall of the gas cell. It will be useful with rigid airships to arrange such protection between the outer 50 cover and the gas cell, thereby creating no new air resistance. In addition the outer cover itself may also be reinforced by another layer of fabric attached to it either inside or outside.

In the drawing constituting part of this 55 application and showing an example em-

bodying my invention with the propeller illustrated diagrammatically, Fig. 1 is a cross section through a portion of the ship, and Fig. 2 is a view of a portion of the outer cover with certain parts removed.

In both views the longitudinal girders of the airship are designated as *a* and the outer cover situated on top of them as *b*. The wall of the gas cell is shown at *c*. The propeller *d* is situated outside of the ship. 60

The protective layer *e* is arranged inside of the outer cover *b* and passes between the longitudinal girders and the outer cover, but it is not held taut like the latter but lies loosely in the jacket space between the outer 65 cover and the wall of gas cell. It may be fastened in any suitable way to the longitudinal girders. Instead of having one piece passing over the longitudinal girders several smaller pieces reaching from girder 70 to girder may be arranged. Also several superposed layers may be used whereof all may be loose or only some may be loose and others taut. For the purpose of preventing the wall of the gas cell *c* from bulging so 75 far as to touch the protective layer *e*, tension members such as wires *f* or the like may be arranged in a net-like manner. They also serve for steadyng the protective layer *e*, as may be seen from the drawings. Out- 80 side or inside of the outer cover a reinforcing layer *g* may be attached to it. 85

My invention may be made use of by different kinds of airships and it may also serve for protecting other fragile parts of 90 aircraft subject to destruction by pieces of ice or the like for example containers of gas or liquid, instruments or the like. Therefore I do not limit myself to the details 95 of the example described or shown in the drawing as many variations will occur to persons skilled in the art.

Claims.

1. An airship comprising an outer cover, a fragile part inside of said cover and spaced apart therefrom, a propeller outside of said cover and a protective layer of sheet-like material arranged between said outer cover and said fragile part and spaced from the latter.

2. An airship comprising an outer cover, a fragile part inside of said cover and spaced apart therefrom, a propeller outside of said cover and a protective layer of fabric loosely and resiliently arranged between said 110

outer cover and said fragile part and spaced from the latter.

3. An airship comprising an outer cover, a gas cell inside of said cover, a propeller outside of said cover, a protective layer of fabric between said outer cover and the wall of said gas cell, and net-like arranged tension members steadyng the outside of the wall of said gas cell and serving for keeping the same from bulging to any great extent.

4. An airship comprising an outer cover, a gas cell inside of said cover, a propeller outside of said cover, a protective layer of fabric loosely and resiliently arranged between said outer cover and the wall of said gas cell, and net-like arranged tension members steadyng the outside of the wall of said gas cell and serving for keeping the same from bulging to any great extent. 15

LUDWIG DÜRR.
